UNITED STATES PATENT OFFICE.

RUDOLF EICKEMEYER, OF YONKERS, NEW YORK.

SPEAKING-TELEPHONE.

SPECIFICATION forming part of Letters Patent No. 249,233, dated November 8, 1881.

Application filed July 13, 1881. (No model.)

To all whom it may concern:

Be it known that I, RUDOLF EICKEMEYER, of Yonkers, in the State of New York, have invented a new and useful Improvement in Speaking-Telephones, of which the following is a specification.

The invention relates to that class of speaking-telephones in which the transmission of articulate speech is due to the variations in the resistance of the electric circuit; and it consists in an improved device for producing said variations in resistance, the essential parts thereof being a platinum strip forming one electrode, and arranged to partake of the vibrations of an ordinary diaphragm, and a triangular film of carbon, slightly curved, as hereinafter described, and forming the second electrode. The platinum strip and carbon film are placed lengthwise with each other, and are always in contact; but as the platinum strip takes up the vibrations of the diaphragm the surface of the film of carbon remaining in contact with the platinum strip, or with which contact is made by the platinum strip, varies both lengthwise and breadthwise. The film of carbon is exceedingly thin, and is always at rest.

In the drawings, Figure 1 is a plan of a transmitting-instrument embodying my invention, the diaphragm and a part of the mouth-piece having been removed. Fig. 2 is a vertical section of said instrument. Fig. 3 gives two views of a rubber dampener. Fig. 4 is a diagram illustrating, so far as is necessary, the mode of operation. Fig. 5 is a partial section, on an enlarged and exaggerated scale, to show the relative locations of the electrodes and parts to which they are attached. Fig. 6 is a detail, to which especial reference is hereinafter made.

A is the bed-piece. B is the base of a frame, adjustable upon the bed-piece by means of screws s' s^2 , working in slots t' t^2 , as shown. C is the upper part of said frame, furnishing a seat for the diaphragm D, which is held therein by a mouth-piece, E, in the ordinary manner, there being a damping-cushion, e, around the edge of the diaphragm. The base and top part of the frame are connected, as shown, by three posts, F, made adjustable in length by means of thumb-screws G.

H is a plate of ivory, hard rubber, or glass, supported by two metallic posts, J J', in which, respectively, are the binding-screws a a' , to which are attached the line-wires l l . A hole is cut through the middle of the plate H, opposite the center of the diaphragm, and in this hole is set a piece of platinum, p, which is connected with the metallic post J' by a wire, w. There is also on the top of the plate H a film of carbon, c, triangular in shape, forming one of the electrodes, as stated above, the wider part of the film resting upon the piece of platinum p, which fills the hole in the plate H.

K is the strip of platinum referred to above as the other electrode. It is held in place, in part upon and in part above the plate H, by two bands, b b, screwed to the plate H, there being a bridge or block, d, to separate the platinum strip from the plate at one end, as shown. One end of the platinum strip is in contact with the metallic post J, as shown.

P is a rod firmly secured to the platinum strip K, and also to the diaphragm D, whereby the vibrations of the diaphragm are communicated to the electrode or platinum strip.

L is a bar, screwed at one end to the inner side of the top portion of the frame, and two rubber dampeners, r r, one on either side of the diaphragm, are held between this bar and the mouth-piece. These rubbers serve also as washers for the nut and flange used in securing the part P to the diaphragm, as shown in Fig. 6.

R is an adjusting-screw, its upper end pressing against the plate H under that portion covered by the carbon film c, at about the middle of the latter longitudinally, and giving to both plate and film a slight curve longitudinally in the normal adjustment of the apparatus. The relation of the electrodes to each other when at rest, or the initial resistance of the line, is regulated by this screw R, and it is obvious from the foregoing description that this relation and the resistance of the line will vary with the vibrations of the diaphragm. This is shown by the diagram at Fig. 4, where the three perpendicular cross-lines in the lower part of the figure illustrate the variations in the width of the film in contact with the platinum strip, while the tangential lines to the

plate H in the upper part of the figure illustrate the variations in the length of carbon film in contact with the platinum strip, the film itself not being shown in the upper part of the figure, 5 on account of its exceeding thinness.

An induction-coil may be used with this telephone in the ordinary manner.

I claim—

1. The platinum strip K, partaking of the 10 vibrations of the diaphragm and forming one of the electrodes, in combination with the diaphragm and a film of carbon, with an insulating bed therefor, the said film being of varying width and curved longitudinally upon its 15 said bed, and forming the second electrode, substantially as described.

2. In a speaking-telephone, substantially as described, the means for adjusting the second electrode and giving to it a curved surface consisting of the carbon film itself, the plate H, 20 clamped at each end, and the adjusting-screw R.

3. The diaphragm D, post P, and platinum strip K, in combination with the plate H, bridge d, platinum plug p, carbon film e, and line-connections, substantially as described.

RUDOLF EICKEMEYER.
